SKIRT HEM MARKER

Abraham M. Schwartz, Brooklyn, N. Y.

Application January 29, 1947, Serial No. 725,055

2 Claims. (Cl. 33—10)

1

This invention relates to skirt hem markers. It is an object of the present invention to provide a skirt hem marker with a platform on which the person having the skirt fitted may stand and wherein the powder box can be adjusted inwardly and outwardly toward the skirt while also being adapted to be adjusted to different heights upon a vertically upstanding structure incorporating a measuring member.

It is another object of the invention to provide a skirt hem marker which is of simple construction, inexpensive to manufacture and efficient in operation.

According to the invention, there is provided a platform on which the person wearing the skirt to be measured may stand, and the measuring member extends upwardly alongside the platform.

Upon the upstanding measuring member, which preferably carries a backing member, there is connected an adjusting block having openings extending through the opposite sides thereof; and by way of these openings, a horizontal U-shaped structure can be adjusted toward and away from the person. This U-shaped structure at the free ends of the legs of the U carries the powder box, and extending rearwardly from the latter is a tube which is also supported by the adjusting block.

The U-shaped member at its rear portion, where the bight of the U is located, thus provides an adjusting handle; which handle at one end may be formed to provide a rest for the bulb bottom uses of the latter.

Also provided by the invention is a means for readily conveniently adjusting the block vertically along the length of the measuring member; and the invention further provides a means, preferably including a crank handle, for conveniently effecting horizontal shift of the U-shaped member thereby to adjust the powder box toward and away from the person on the platform.

The upstanding structure incorporating the measuring member is preferably provided at its rear side with calibrations corresponding to those carried on the front side of the measuring member, and a mirror is mounted on said upstanding structure and is inclined or inclinable so that a person standing on the platform or alongside the same can read from the mirror the height to which the powder box has been adjusted. Said calibrations are preferably in terms of the skirt length measured down from the waist of the wearer.

2

Also according to the invention, the measuring member is rotatable about the platform on which the person wearing the skirt stands, so that with the person standing in one position, the skirt may be marked all around with perfect accuracy.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a perspective view of a now preferred embodiment of the skirt hem marker of the present invention.

Fig. 2 is a transverse cross sectional view taken through the upstanding structure which incorporates the measuring member, and thus taken at a height such that the view also shows in top plan the adjusting block and the parts associated therewith.

Fig. 3 is a detail cross sectional view taken on line 3—3 of Fig. 2 looking in the direction of the arrows.

Fig. 4 is a fragmentary side elevational view of the adjusting block, the powder box, and other certain adjacent parts.

Fig. 5 is a vertical section taken through the powder box on line 5—5 of Fig. 2 looking in the direction of the arrows.

Fig. 6 is a horizontal section taken through the block on line 6—6 of Fig. 4.

Fig. 7 is a detail view in vertical section, taken on the line 7—7 of Fig. 1 and looking in the direction of the arrows.

Referring now to the drawing in detail, 15 represents a base shown as having feet 15' adapted to engage with the floor. Above the main lower part of the base the same extends upwardly as a reduced cylindrical portion 15'', and on the latter is fixed, as indicated at 16, the circular platform 17. Loosely sleeving the portion 15'' is the ring-shaped end portion 18 of the arm 19.

To the outer end of the arm 19 is secured the lower end of a measuring scale 21. This measuring scale is here shown as backed by an L-shaped backing member 22 having its bottom limb 23 lying under and suitably rigidly connected to the laterally extending portion 19 of the base 15.

Vertically adjustable upon the measuring and backing members is a block 24 of molded plastic material or the like having holes 25 extending 55 through the same at opposite sides thereof,

through which are extended for longitudinal adjustment the legs 26 of the U-shaped member 27, the bight of which is marked 27'.

Block 24 has extended therethrough vertically an opening 28 of oblong cross section for fitting around the upstanding structure which includes the measuring member and the backing member 22; and the block 24 has threadedly mounted thereon a long set screw 29 having a wing-nut type of head, so that this screw may be readily manually tightened up to hold the block 24 at any desired elevation along the length of the measuring member.

For adjusting the U-shaped member 27 to project the free ends of its legs 26 more or less forward of the measuring member 21, a shaft 30 is suitably non-withdrawable journaled in an end portion of the block 24. This shaft at the exterior of said block has secured thereon a crank handle 39'. The shaft 30 at its inner end fixedly carries a small spur gear 30a, which gear is housed in a recess 30b in the upper portion of block 24; and the teeth of this gear mesh with a line of rack teeth 30c extending along the top of the adjacent leg 27 of the U-shaped member 26, such rack teeth conveniently provided by the application of milling cutters across said leg. Thus the U-shaped member 27 can be readily manually adjusted longitudinally of its legs 26 through the holes 25 in the block 24.

To the forward ends of the legs 26 there is connected a powder box 31, as by means of sleeves providing rearwardly extending portions 32 at opposite sides of the powder box and having set screws 33. The box 34 may have a removable cover, as of the hinged type (not shown); but as the box is here illustrated it has an opening 34 in its permanently closed top, such opening being closable by a screw cap 34'. When said cap is temporarily removed the supply of powder in the box can be replenished. In the front edge of the box are small apertures 35 through which the powder is blown upon the skirt.

Connected to the top of the box is a flexible tube 36 which passes through a hole in one side of the block 24, and in which, ahead of said block, is interposed an air build-up chamber in a hollow fitment 37. The rear end of the tube, in back of the block 24, terminates in a bulb 38, which is manually pressed when powder is to be dispensed. Slight pressure on the bulb causes the air in the hollow fitment 37 to act booster fashion to discharge powder at relatively high velocity through the apertures 35 of the powder box.

When the bulb is not in use, the same may rest by its own weight on a reversely bent portion 39 of the U-shaped member 27, when the portion of the tube 36 extending between the bulb and the block 24 although flexible is of fairly stiffly flexible nature.

Mounted on the upper end of the upstanding structure incorporating the measuring member 21 and the backing strip 22, is a bracket 40 on which is mounted a mirror 41 desirably of metal, chromium plated, the mirror being mounted on an end of the bracket 40 by means of an attachment 42 of the swivel-clampnut type, whereby the reflective angle of the mirror may be readily adjusted as desired.

It is to be understood that this skirt hem marker may be controlled by an electric motor and the powder box may be equipped with suitable electric means for spraying the powder.

While I have illustrated and described the pre-

ferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:

10. A skirt hem marker comprising, a horizontal base member having an offset portion, a supporting platform for the skirt wearer secured upon said base, a vertical element supported by said offset portion, a block member slidably disposed on said vertical element and provided with means for selectively positioning it thereon, elongated parallel arms supported horizontally by said block one on either side of said vertical element, rack and pinion means permitting manual movement 15 of said arms with respect to said block, a powder box supported between adjacent ends of said arms above said platform, means spaced from and connected to said powder box for supplying a pumping pressure thereinto, said means comprising a manually operated bulb, a flexible tube having one of its ends connected with said bulb, said block having an opening in one side thereof, the other end of said tube extending through said opening and connecting with an air booster 20 chamber, and a tube connecting said booster with said powder box.

2. A device for marking the hem of a skirt while the same is being worn comprising, a horizontal base member having an offset portion, a platform disposed on and secured to said base for supporting the wearer, a scaled measuring member secured to and extending vertically from the offset portion of said base, a block member vertically slideably secured on said measuring member and having means for selectively adjustable attachment therewith, a pair of parallel arms having slideable horizontal support in said block member spaced one on either side of said measuring member with one pair of adjacent ends 35 thereof disposed above said platform, a cross bar interconnecting those adjacent ends of said arms remote to said platform, one of said arms being provided with a toothed rack through a portion thereof, a toothed pinion provided with a handle being revolvably mounted on said block in engagement with said arm rack, a spraying powder box supported on the adjacent ends of said arms disposed above said platform, a means for supplying air pressure to said box supported 40 remote thereto and interconnected therewith, said means comprising a manually operated bulb, a flexible tube having one of its ends connected with said bulb, said block having an opening in one side thereof, the other end of said tube extending through said opening and connecting with an air booster chamber, and a tube connecting said booster with said powder box.
